UNITED STATES PATENT OFFICE.

EUGEN O. BREUNING, OF HOBOKEN, NEW JERSEY.

CONTROLLING DEVICE FOR PHONOGRAHS.

1,373,994.

Specification of Letters Patent.

Patented Apr. 5, 1921.

Application filed March 18, 1920. Serial No. 366,750.

To all whom it may concern:

Be it known that I, EUGEN O. BREUNING, a citizen of Germany, and resident of Hoboken, county of Hudson, and State of New Jersey, have invented a new and Improved Controlling Device for Phonographs, of which the following is a full, clear, and exact description.

This invention relates to phonographs and 10 more particularly to a device for controlling the operation of the same.

The principal object of the present invention is to provide a device of the character described, in the nature of an attachment for 15 phonographs which is designed to actuate the phonograph at a predetermined time.

Another object of the invention is to provide a time controlled mechanism for actuating the turn table of a phonograph prior 20 to the presentation of the needle in contact with the record.

A further object of the invention is to provide a controlling mechanism for phonographs which is applicable to clocks of various standard types.

A still further object of the invention is to provide in combination with a time controlled phonograph actuating mechanism, means for automatically stopping the 30 phonograph.

Another object of the invention is to provide a device of the character described reversible in order to render the same applicable to phonographs having various arrangements of the tone arm.

A further object of the invention is to provide a device of the character described which is simple in construction and operation, inexpensive to manufacture and efficient in its purpose.

With these and other objects in view, some of which will be more readily apparent when the nature, purpose and operation is better understood from the following description and claims, reference is had to the accompanying drawings forming a part of this application and in which;

Figure 1 is a plan view of the attachment illustrating the same applied to a phonograph.

Fig. 2 is a fragmentary plan view illustrating the attachment as applied to a phonograph having a tone arm arranged reversely to that shown in Fig. 1 of the drawings.

Fig. 3 is a longitudinal sectional view through the attachment illustrating the arrangement of parts when the same are set.

Fig. 4 is a similar view illustrating the arrangement of parts after the same have 60 been operated to start the phonograph.

Fig. 5 is a plan view of the attachment with the housing removed and parts in section, the dotted lines illustrating the arrangement of the reversible elements for the 65 application of the device to a phonograph having a different arrangement of the tone arm.

Fig. 6 is a side elevation of the attachment.

Fig. 7 is a front end view of the same.

Fig. 8 is a perspective view of the removable housing.

Fig. 9 is a collective view illustrating the manner in which the attachment is applied 75 to the motor board.

Fig. 10 is a detail fragmentary sectional view of a portion of the attaching means.

Fig. 11 is an enlarged fragmentary plan view of the friction brake for the turn table.

Fig. 12 is a fragmentary longitudinal sectional view taken approximately on the line 12-12 of Fig. 5.

Fig. 13 is a fragmentary transverse sectional view taken approximately on the line 85 13-13 of Fig. 4.

Referring to the drawings by characters of reference which denote like parts throughout the several views thereof, A designates the motor board of a phonograph having 90 the usual rotary turn table B mounted thereon for the reception of the record C. In the type of phonograph illustrated in Fig. 1 of the drawings the tone arm D is disposed at the right hand side of the 95 phonograph and the same is provided with the usual sound box E and needle F.

The controlling device is designated generally by the character G and the same is designed to be operated by any standard 100 form of clock H provided with an alarm mechanism.

The controlling device includes a base plate 10 having a vertical end wall 11 and a side wall 12. An angular bracket 13 is 105 mounted on the end wall 11 by a set screw 14 to permit of vertical adjustments of the same. A horizontal shelf 15 is supported by the angular bracket 13 for universal horizontal adjustments by means of the set 110

screw 16. The shelf 15 is preferably of arcuate formation to conform to and closely embrace the clock H and the same is provided with the slots 17 to receive the feet of the clock. A pair of feet engaging and retaining members 18 are secured to the shelf adjacent the slots 17 and the same are normally forced into engaging and retaining position by means of a spring 19.

10 The means for detachably associating the device with the motor board A of the graphophone comprises an attaching plate 20 which is secured to the motor board by means of the fastening screws 21. The forward end 15 of the attaching plate is provided with vertically disposed side flanges 22 between which the base plate is designed to lie. A pair of angular flanges 23 are formed medially of the sides of the attaching plate and the same are designed to co-act with notches 24 in the side edges of the base plate. The attaching plate is provided with a headed stud 25 which is adapted to be received by the key hole slot 26 in the base plate. A 25 vertically movable spring pressed latch 27 is arranged in the housing 28 and the lower end of said catch is designed to enter the latch opening 29 in the attaching plate for locking the device to the attaching plate 30 after the flanges 23 and the stud 25 have been properly positioned in the notches 24 and the key hole slot 26. The upper end of the latch 27 is provided with an exteriorly disposed handle 30 for releasing the same.

15 A beveled gear 31 is rotatably mounted on a stub shaft 32 positioned in the upper portion of the side wall 12 and a housing 33 for covering the same supports a drive shaft 34 mounted in said housing at a right angle to the axial center of the stub shaft and beveled gear. A beveled pinion 35 is keyed to the drive shaft which is shiftable longitudinally in the housing 33 to respectively engage or disengage said pinion with the beveled gear. A coiled expansion spring 36 is disposed between the gear and an angle bracket 37 for normally effecting the disengagement of the pinion with the gear and a clutch lever 38 having a forked portion 39 is adapted to engage an annular groove 40 in the sleeve 41 which is keyed to the forward extremity of the drive shaft whereby to retain the pinion in engagement with the gear. The extremity of the sleeve 41 is 55 bifurcated as at 42 to provide a yoke for embracing the alarm key 43 of the clock H. The opposite extremity of the drive shaft 34 projects outwardly of the casing through the angle bracket 37 and has secured thereto a manipulating knob 44. The rear face of the beveled gear 31 is provided with a pair of diametrically disposed studs 45 and 46 which project through the arcuate slots 47 and 48 formed in the side wall 12. A bell crank lever 49 is pivoted as at 50 to the inner side

of the side wall 12 at a point below the stub shaft 32. The upper arm 51 of the bell crank lever is adapted to be connected by means of a link 52 to either one of the studs 45 or 46. The extremity of the arm 51 is 70 provided with a slot 53 and the wall 12 is provided with a slot 54 in which the connecting pin 55 is adapted to operate. The lower arm 56 of the bell crank lever is operatively connected with a slide 57 by means of a pin 58. The side flange 59 of the slide guides the same in its movements through the medium of the engagement of the pins 60 with the slots 61 provided in the lower portion of the wall 12. The rear extremity 80 of the slide is provided with upturned ears 62 having aligned openings for the reception of a transverse pin 63 upon which is mounted for vertical swinging movement a yoke 64.

85 The means for raising and lowering the tone arm D of the graphophone comprises a supporting arm 65 which is vertically adjustable in the sleeve 66, said sleeve being mounted on the vertical shaft 67 which is provided on the base plate 10. The slide is 90 provided with vertically disposed aligned ears 68 on its opposite side edges and the same are provided with inclined slots 69 for the reception of the trunnions 70 projecting from opposite sides of the sleeve 66 whereby 95 upon longitudinal movement of the slide a raising and lowering of the sleeve 66 will be effected to lift or drop the supporting arm 65. The bottom wall of the slide is slotted as at 71 to accommodate the vertical 100 shaft 67.

105 The rear end of the base plate 10 is provided adjacent its extremity with a vertical boss 72 constituting a bearing for the horizontal friction brake lever 73 pivoted thereon as at 74. The lever is of angular formation and the free extremity of the same constitutes a brake shoe 75 which is adapted to be moved into and out of engagement with the peripheral edge of the turn table B. 110 The pivoted portion of the lever is provided with an extension constituting an actuating nose 76 which is designed to co-act with the cam face 77 of the yoke 64 for imparting a throw to the free end of the 115 brake lever whereby to disengage the brake shoe 75 and break its frictional contact with the turn table.

120 The means for retaining the lever 73 in its position to dispose the brake shoe out of frictional engagement with the turn table includes the spring pressed catch 78 which is provided with a finger 79 adapted to engage the notch 80 in the lever 73 when the same registers therewith. A coiled contractile spring 81 secured at one extremity to a stud 82 on the base plate and at its opposite extremity to a stud 83 on the nose 76 serves to normally tension the brake lever to force the brake shoe against the turn table and 125 130

the catch 78 serves to retain the brake shoe out of engagement with the turn table against the action of the spring 81.

Means is also provided for stopping the machine when the playing of the record has been completed and said means is in the nature of a releasing device which operates on the spring pressed catch 78 to disengage the finger 79 from the notch 80 whereby to permit the spring 81 to throw the brake shoe into contact with the turn table. The releasing device is illustrated at 84 and the same is in the nature of a bifurcated plate mounted on a vertical shaft 85 carried by the extremity of the base plate the furcations 86 of the plate form inwardly extending beveled terminals 87 which are adapted to engage with the down turned V-shaped end 88 of the spring pressed catch 78 whereby upon movement of the plate in either direction a disengagement of the finger 79 with the notch 80 will result, in order to permit the stopping device to function automatically. The vertical shaft 85 is provided with a bore 25 for the reception of a crank 89, the upturned outer extremity 90 of which lies in the path of movement of the tone arm which is adapted to contact therewith when the same has been moved across the record and the playing of the same completed. The brake lever and the releasing device may function if desired independently as an automatic stop for a phonograph and in order to provide a manual manipulating means for moving 30 the lever 73, the same has been provided with oppositely disposed ears 91.

A removable casing 92 for housing the mechanism is provided and the same is retained in place by means of a bolt and finger 40 nut 93. A lug 94 is also provided on the base plate and is adapted to enter the socket 95 for the proper positioning of the casing relative thereof.

In operation of the device, the alarm mechanism of the clock is wound up by its key 43 and the same is positioned on the shelf as illustrated. The clutch lever 38 is disengaged from the groove 40 and the same is rotated to properly position the alarm key 45 embracing yoke 42 over the key 43, the beveled gear 31 having been previously rotated to dispose the stud 46 at the upper extremity of the arcuate slot 47. This arrangement of the stud due to its connection with the link 52 and the bell crank lever 49 disposes the yoke 64 over the actuating nose 76 so that the extremity of said nose contacts with the cam surface 77. The brake lever 73 is 50 swung to a position to dispose the brake shoe 75 in frictional contact with the turn table B of the phonograph. The upturned outer extremity of the crank is positioned in the path of movement of the tone arm D at a point where the tone arm will engage the 55 same when the playing of the record has

been completed. The alarm mechanism of the clock is set in the usual manner to operate at a predetermined time and when such a time arrives the alarm key 43 will rotate the drive shaft and the pinion 35 which 70 has been engaged with the beveled gear 31. As the gear 31 turns the upper arm 51 of the path crank lever will be moved downwardly through the medium of the link 52, thus throwing the arm 56 forward to move 75 the slide in the same direction. As the slide moves forward the cam surface 77 co-acting with the nose 76 will throw the friction brake lever to disengage the brake shoe 75 from frictional contact with the turn table 80 and as the notch 80 in the lever registers with the fingers 79 of the spring pressed catch, said fingers will enter said notch to retain the brake lever in inactive position. Simultaneously the engagement of the inclined slots 69 with the trunnions 70 on the sleeve will effect a downward movement of the same permitting the supporting arm 65 to lower the tone arm and sound box until the needle F contacts with the record. It 90 will thus be seen that the turn table and record will have completed several revolutions prior to the contact of the needle with the record for properly starting the playing operation. At the time that the playing of 95 the record is completed the tone arm D will have reached and engaged the upturned outer extremity 90 of the crank and the engagement with the same will rotate the shaft 85 a sufficient distance to swing 100 the releasing plate 84, the engagement of one of the beveled terminals 87 with the V-shaped end 88 of the catch serving to disengage the finger 79 from the notch 80. The spring 81 will then throw the brake lever 73 to a position to brake the turn table by the engagement of the brake shoe 75 therewith, resulting in the stopping of the machine. In order to reset the starting mechanism, it is only necessary to rotate the drive shaft in 110 the opposite direction by means of the knob 44. This will return the stud 46 to the upper end of the arcuate slot 47 which will exert an upward pull on the link to throw the lower arm 56 of the bell crank lever to 115 the rear and effect a resulting movement of the slide. As the end of the yoke which is beveled as at 77^a engages with the nose 76 it will ride up over the same and gravitate behind it to again dispose the cam surface 77 in engagement therewith.

In order to apply the device to a machine which is provided with a tone arm arranged at the left hand side, the mechanism is provided with reversible elements which it is 125 thought will be obvious from the showing in dotted lines in Fig. 5 of the drawings. In order to apply the device to a machine with a tone arm positioned at the left hand side thereof, the brake lever is reversed by re- 130

moving the screw pivot 74 and turning the same over; the support 65 is swung to the opposite side and the crank is turned as illustrated in dotted lines. The inturned beveled extremities 87 will operate to disengage the finger 79 by a swinging of the plate 84 in either direction and the actuating nose 76 engages the opposite cam surface 77 of the yoke. The second stud 45 formed on the 10 beveled gear 31 is provided in event that the device is used in connection with an alarm key which rotates oppositely to the one illustrated, in which instance it is only necessary to attach the upper end of the link to said 15 stud.

It will be further understood that when desired the brake lever and the brake releasing device may be utilized independently of the starting mechanism as an automatic stop 20 for a graphophone and it will be appreciated that the device is readily attached or detached by manipulating the handle 30 to disengage the lower end of the latch 27 from the opening in the attaching plate.

25 While there has been illustrated and described a single and preferred embodiment of the invention, it is understood that the same is merely illustrative of one form and changes and variations in the structure 30 which do not depart from the appended claims may be made when found expedient.

Having thus described my invention, what I claim as new and desire to secure by Letters Patent; is,

35 1. Means for controlling the operation of a phonograph comprising a vertically movable tone arm support, slidable means for effecting vertical movements of the same, and a device carried by said means adapted 40 to co-act with the brake for causing the release of the same from the turn table upon movement of the slidable means in a direction to effect the lowering of the tone arm support.

45 2. Means for controlling the operation of a phonograph comprising a vertically movable tone arm support, slidable means for effecting vertical movements of the same, a device carried by said means adapted to co- 50 act with the brake for causing the release of the same from the turn table upon movement of the slidable means in a direction to effect the lowering of the tone arm support, means for retaining the brake out of engagement 55 with the turn table, and means adapted to be operated by the tone arm for releasing said retaining means.

60 3. Means for controlling the operation of a phonograph comprising a vertically movable tone arm support, slidable means for effecting vertical movements of the same, a device carried by said means adapted to co-act with the brake for causing the release of the same from the turn table upon movement 65 of the slidable means in a direction to

effect the lowering of the tone arm support, and means for actuating the slidable means.

4. Means for controlling the operation of a phonograph comprising a vertically movable tone arm support, slidable means for effecting vertical movements of the same, a device carried by said means adapted to co-act with the brake for causing the release of the same from the turn table upon movement of the slidable means in a direction to effect 70 the lowering of the tone arm support, and time controlled means for actuating the slid- 75 able means.

5. The combination with a phonograph, means for controlling the operation of the 80 same, comprising a vertically movable tone arm, an operating slide, means formed re- 85 spectively on the slide and tone arm adapted to co-act upon movement of the slide to effect vertical movements of the tone arm sup- port, and means on the slide adapted to co-act with the brake for causing the release of the same from the turn table upon move- 90 ment of the slide in the direction for effecting the lowering of the tone arm support. 95

6. The combination with a phonograph, means for controlling the operation of the 100 same, comprising a vertically movable tone arm, an operating slide, means formed re- 105 spectively on the slide and tone arm adapted to co-act upon movement of the slide to effect vertical movements of the tone arm support, means on the slide adapted to co-act with the brake for causing the release of the same from the turn table upon move- 110 ment of the slide in the direction for effecting the lowering of the tone arm support, and means for actuating the slide.

7. The combination with a phonograph, means for controlling the operation of the 115 same, comprising a vertically movable tone arm, an operating slide, means formed re- 120 spectively on the slide and tone arm adapted to co-act upon movement of the slide to effect vertical movements of the tone arm support, means on the slide adapted to co-act with the brake for causing the release of the same from the turn table upon move- 125 ment of the slide in the direction for effecting the lowering of the tone arm support, and time controlled means for actuating the slide.

8. The combination with a phonograph, means for controlling the operation of the 130 same, comprising a vertically movable tone arm, an operating slide, means formed re- 135 spectively on the slide and tone arm adapted to co-act upon movement of the slide to effect vertical movements of the tone arm support, means on the slide adapted to co-act with the brake for causing the release of the same from the turn table upon move- 140 ment of the slide in the direction for effecting the lowering of the tone arm support, time controlled means for actuating the 145

- slide, means for retaining the brake out of engagement with the turn table and adjustable means adapted to be operated by the tone arm for releasing said retaining means.
- 5 9. The combination with a clock having an alarm mechanism, of a device for starting a phonograph comprising a brake normally adapted to frictionally engage the turn table of said phonograph, and a vertically movable sleeve having a tone arm support, an operating slide, means formed respectively on the slide and the sleeve adapted to co-act whereby to effect vertical movements of the sleeve, means formed respectively on the slide and the brake adapted to co-act for disengaging the brake from the turn table upon the movement of the slide in a direction for effecting the lowering of said sleeve, and mechanism for moving the slide, said mechanism being adapted to be actuated by the alarm mechanism of the clock whereby to effect a movement of the slide in the direction to disengage the brake and lower the sleeve, means for retaining the brake out of engagement with the turn table, and means adapted to be operated by the tone arm for releasing said retaining means. 40
- 10 15 20 25 30 35 40 45 50 55 60 65 70
11. The combination with a clock having an alarm mechanism, of a device for starting a phonograph comprising a brake normally adapted to frictionally engage the turn table of said phonograph, and a vertically movable sleeve having a tone arm support, an operating slide, means formed respectively on the slide and the sleeve adapted to co-act whereby to effect vertical movements of the sleeve, means formed respectively on the slide and the brake adapted to co-act for disengaging the brake from the turn table upon the movement of the slide in a direction for effecting the lowering of said sleeve, and mechanism for moving the slide, said mechanism being adapted to be actuated by the alarm mechanism of the clock whereby to effect a movement of the slide in the direction to disengage the brake and lower the sleeve, said mechanism also serving as a means for rewinding the alarm mechanism and resetting the slide. 50 55 60 65 70
